CLAIM

The ornamental design for a display screen with animated graphical user interface for a vehicle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first image in a sequence for a display screen with animated graphical user interface for a vehicle, showing this new design;

FIG. 2 is a front view of a second image in a sequence thereof; and,

FIG. 3 is a front view of a third image in a sequence thereof. The appearance of the animated image transitions between the images shown in FIGS. 1-3. The process or period in which one image transitions to another forms no part of the claimed design. The color drawings form parts of the claimed design.

The broken lines depicting the display screen form no part of the claimed design.
